UNITED STATES PATENT OFFICE.

WILLIAM T. INNES, OF PHILADELPHIA, PENNSYLVANIA.

BANK DEPOSIT SLIP.

Application filed December 9, 1921. Serial No. 521,081.

To all whom it may concern:

Be it known that I, WILLIAM T. INNES, a citizen of the United States, residing at Philadelphia, county of Philadelphia, and

5 State of Pennsylvania, have invented a new and useful Improvement in Bank Deposit Slips, of which the following is a full, clear, and exact description, reference being had to the accompanying drawings, which form 10 a part of this specification.

This invention relates to an improvement in bank deposit books of the club type, which are issued for deposits of different amounts which are to be made in installments on or 15 before predetermined dates.

Considerable time is required daily in banks having a large number of depositors of this character to sort and balance the deposit slips and the amount received. The 20 slips are usually colored or printed in such a manner that the teller can readily sort the slips and place those of one denomination on one pile and those of other denominations on other piles or stacks, and after sorting the 25 slips are counted.

It frequently occurs that the slips and amount deposited do not balance and is frequently caused by the teller misplacing one or more slips in the wrong stack or stacks. 30 When this occurs, it is necessary for the teller to leaf over the stacks, properly place the misplaced slips, and then recount.

The object of my invention is to provide a system or arrangement of slips whereby the 35 teller can stack the deposit slips at the end of the day or during the day when the deposits are made whereby he can see at a glance whether any of the slips are placed in the wrong stacks.

40 Another object of my invention is to provide a rack for receiving the slips, which is adapted to maintain the slips in order.

The precise nature of my invention will be best understood by reference to the accompanying drawings, which will now be described, it being premised, however, that changes may be made in the details of construction without departing from the spirit and scope of my invention as defined in the 50 appended claims.

Fig. 1 of the drawings illustrates one form of deposit book made in accordance with my invention showing the top page as printed.

Fig. 2 is a similar view after the top page 55 has been stamped and signed.

Fig. 3 is a perspective view of a holder for deposit slips.

Fig. 4 is a face of a modified form of deposit slip separated from its stub.

The books as issued each contain a predetermined number of pages or leaves on which are designated the amount of the installment to be paid and the time when such installment is to be paid. The book shown in the drawings is illustrative of a book of the "fifty cent" denomination and in which *a* designates the stub which is left in the book and *b* the deposit slip to be severed therefrom. The leaves are printed and perforated 70 as indicated at *c* or provided with a weakened portion in any desired manner so that the deposit slips can readily be severed from their stubs along a predetermined line. Each deposit slip is also provided with one 75 or more perforations such as *d* and *e*. These holes *d* and *e* are located in precisely the same positions in all of the slips in books of the fifty cent denomination issued by a bank, while the slips of each other denomination have similar holes which register 80 with each other but are out of register with slips of all other denominations.

The stubs may also be provided with a blank space *f*, while the slip may be provided with a similar space *g* in which the date on which the deposit is made may be stamped, as indicated at *h* in Fig. 2.

The books are issued by the bank to depositors of the desired denomination and 90 when the depositor makes a deposit, he signs the required number of slips to cover the amount of the deposit, passes the book and the money to the teller, who stamps both the stub and slip and signs the stub, 95 as indicated in Fig. 2. The teller then separates the stamped and signed slips from the stubs, returns the book to the depositor, and places the slip or slips in a holder, such as shown at *x* in Fig. 3, for the slips of the 100 denomination deposited.

In the case illustrated, the slips are placed in the first compartment designated 50¢, which is provided with pins *d'* and *e'* which are adapted to enter holes *d* and *e*, 105 respectively, in the slips *b*. The other compartments designated \$1.00, \$2.00, and \$5.00 are provided with similar pins *d²*, *e²*; *d³*, *e³*;

and c^4 , d^4 , respectively, and as the pins in the different compartments are placed in different positions, it will be impossible for the teller to place the slips in the wrong compartment.

In Fig. 4 I have shown a modified form of blank in which the slip is merely provided with notches d^5 and e^5 arranged to engage positioning pins or members of the holder.

This provision of registering means on the slips and the holders provides means whereby the teller can readily stack the slips as received and can readily see when placing the slip whether he places the slip in the proper compartment, as the registering devices on the slips and the compartments will not register unless the slips are properly positioned.

This stacking and checking of the slips as received saves time for the teller, as he is assured that the deposit slips of this class of deposits are properly sorted when the bank closes, so that it is only necessary for him to count the slips of the different denominations and is sure that there are no misplaced slips, thus enabling him to accurately balance his cash by the simple process of multiplication.

It will be understood that the shape, sizes and number of cooperating registering devices may be varied to increase the combination of such devices.

Having now fully described my invention, what I claim and desire to protect by Letters Patent is:

1. Bank deposit books of the character described, having leaves representing different denominations, each leaf comprising a stub and a separable deposit slip, the stubs of deposit slips of each leaf in a book representing the same denomination, each deposit slip having positioning means to cooperate with a stacking device, the positioning means in the slips of each denomination registering with each other, but out of register with the positioning means of other denominations so that the edges of the slips of each denomination will register with each other when positioned on a stacking device for slips for such denominations.

2. Bank deposit books of the character described having leaves representing different denominations, each comprising a stub and a separable deposit slip, the stubs and deposit slips of each leaf representing the same denomination, each deposit slip having a perforation, the perforations in the slips of each denomination registering with each other but out of register with such perforations in slips of other denominations.

In testimony of which invention, I have hereunto set my hand, at Philadelphia, Pa., on this 23rd day of November, 1921.

WILLIAM T. INNES.
